UNITED STATES PATENT OFFICE.

FRIEDRICH GUSTAV ADOLF HELLER, OF BERLIN, GERMANY, ASSIGNOR TO
SIEMENS & HALSKE, OF SAME PLACE.

CUT-OUT.

SPECIFICATION forming part of Letters Patent No. 411,380, dated September 17, 1889.

Application filed February 8, 1889. Serial No. 299,122. (No model.) Patented in Germany February 28, 1888, No. 45,682; in France March 9, 1888, No. 189,229; in Belgium March 9, 1888, No. 80,948; in Sweden March 9, 1888, No. 1,585; in Italy March 9, 1888, XXII, 23,131, XLV, 446, XXII, 24,509, XLVIII, 50; in Austria-Hungary March 9, 1888, No. 23,175, and No. 40,224, and in Norway March 20, 1888, No. 885.

To all whom it may concern:

Be it known that I, FRIEDRICH GUSTAV ADOLF HELLER, engineer, a subject of the King of Saxony, residing at Berlin, in the 5 Kingdom of Prussia, and German Empire, have invented certain new and useful improvements in self-acting short-circuits for electrical incandescent lamps arranged in series; and I do declare the following to be a 10 full, clear, and exact description of the invention, such as will enable others skilled in the art to which it appertains to make and use the same, reference being had to the accompanying drawings, and to the letters and figures of 15 reference marked thereon, which form a part of this specification.

Letters Patent have been obtained for this invention as follows: in Germany, No. 45,682, dated February 28, 1888; in France, No. 189,229, 20 dated March 9, 1888; in Belgium, No. 80,948, dated March 9, 1888; in Sweden, No. 1,585, dated March 9, 1888; in Norway, No. 885, dated March 20, 1888; in Italy, Reg. Gen. Vol. XXII, No. 23,131, Reg. Att. Vol. XLV, No. 446, and 25 Reg. Gen. Vol. XXII, No. 24,509, Reg. Att. Vol. XLVIII, No. 50, dated March 9, 1888, and in Austria-Hungary, No. 23,175 and No. 40,224, dated March 9, 1888.

This invention relates to cut-outs for electric lamps; and it consists in the novel construction and combination of the parts, hereinafter fully described and claimed.

In the drawings, Figure 1 is a side view of a series of three lamps provided with cut-outs according to the present invention, and showing the center lamp cut out of circuit. Fig. 2 is a detail side view of one of the cut-outs drawn to a larger scale.

A are the lamps, which may be of any approved construction, connected to the line-wire in the usual manner.

The automatic short-circuiting shunt or cut-out is applied to each lamp, so that if any

lamp should fail the current in the line-wire will continue to pass through the remaining 45 lamps. Each cut-out consists of two opposed springs *g*, depending from the lower part of each lamp and operatively included in the circuit. The lower ends of these springs are normally kept apart by the small solid body 50 *f*. This body *f* is composed of a mixture of any sort of wax—such as beeswax or paraffine—which melts at a low temperature and is a non-conductor of electricity. With the wax is mixed pulverized graphite or other 55 similar material in sufficient amount to permit a very small current of electricity to pass through said composite body. All the time the lamps are emitting light the wax remains solid, but directly any lamp fails the whole current 60 passes through the springs *g* and body *f*. The resistance of the particles of graphite causes the wax to soften and melt, and the two springs come together, as shown under the middle lamp in the drawings, and cut the 65 said lamp out of the circuit. The materials set forth are preferred, because they will permit the body to melt at a very low temperature and without any smell, and the failing lamp will be cut out without any loss of time. 70

What I claim is—

An automatic electric short-circuiting shunt consisting of opposed springs *g*, connected to the line-wires upon opposite sides of a lamp and depending from the bottom of it, and the 75 non-metallic body *f*, interposed between the lower ends of the said springs and composed of wax and pulverized graphite, substantially as and for the purpose set forth.

In testimony whereof I affix my signature in 80 presence of two witnesses.

FRIEDRICH GUSTAV ADOLF HELLER.
